CHUSETTS

STARTER CONTROL

Application filed March 14, 1929. Serial No. 346,978.

My present invention relates to starter controls, and more particularly to a novel and improved control for the self-starter of a Ford automobile.

- 5 An important object of the present invention resides in the provision of means, operable by manipulation of the spark control rod, to depress the starter rod for starting the engine.
- 10 Another object of the invention is in the provision of such a device, constructed and arranged so that the spark must be retarded to a predetermined degree before operation of the starter switch.
- 15 A still further object of the invention resides in the provision of means, simultaneously and automatically operable on operation of the spark control rod, to advance the gas control rod a sufficient distance to insure 20 an ample starting mixture.

Another feature of the invention consists in the provision of cam mechanism, operated through the medium of the spark control rod, to automatically depress the starter 25 rod.

This last mentioned cam mechanism comprises a fixed cam sleeve mounted beneath the dash board, and a slideable cam sleeve associated therewith, each of said sleeves surrounding the starter rod and the lower or slideable sleeve contacting with a projection on the starter rod whereupon, on operation of the spark control rod in the proper direction, the slideable sleeve will be depressed by 30 the cams on the said fixed sleeve.

Another feature of the invention resides in the provision of spring controlled means which will become operative when the spark has been fully retarded, to prevent further 40 movement of the spark adjusting rod during continued operation of the slideable cam sleeve.

Another and important feature of the present invention, and one which will be instantly appreciated by those skilled in the art, as well as by automobile owners and operators, resides in the fact that I effect no alteration or change in the existing starter switch, starter 45 rod or spark adjusting rod, my present novel

device being an addition rather than a substitution of parts.

My novel device is simple and economical to manufacture, easy to install, simple to operate, and efficient and desirable to a high 55 degree.

The above and other objects of the invention, details of construction, combinations of parts, and advantages, will be hereinafter more fully pointed out, described and claimed. 60

Referring to the drawings, illustrating a preferred embodiment of the present invention,

Fig. 1 is a diagrammatic view of a steering wheel and column of an automobile, illustrating the attachment of my novel device; 65

Fig. 2 is a plan view of the spark control rod and quadrant and gas control rod and quadrant illustrating the operation of my invention; 70

Fig. 3 is a cross-sectional view, on enlarged scale, on the line 3-3 of Fig. 2;

Fig. 4 is a top plan view of my novel starter control mechanism connected to the spark lever and starter rod; 75

Fig. 5 is a longitudinal sectional view of the arm connecting the spark control lever to the slideable cam sleeve, and illustrating the means for controlling the movement of the spark adjusting rod; 80

Fig. 6 is a top plan view of the said arm and the movable sleeve; and

Fig. 7 is a cross-sectional view, on an enlarged scale; illustrating the method of fixing the upper cam sleeve against rotation. 85

Referring now to the drawings, for a particular description of the invention, its construction, assembly and operation, 1 designates the steering column of a Ford automobile, within which the steering shaft 1a is housed, and 2 designates generally the steering wheel. The spark lever which extends downwardly through the steering column, is designated at 3, and carries, at its lower end, a ball stud 4, which is normally held in a socket on the underside of the spark adjusting rod 5. In attaching my novel apparatus, I disconnect the rod 5 from the ball stud 4, and fit said stud 4 in a socket 6 carried by the arm 7, one half of the socket 6 being struck 90

up from a plate 9 which is secured between the two sections of the arm 7 and held in place by the rivets 8 which unite the two sections of said arm.

5 On the side of the arm 7, adjacent to the socket 6, is a ball stud 10 fixed to a plate 11 which in turn is affixed to a yoke 12 having projecting arms 13. The socket in the adjusting rod 5 is snapped over the ball stud 10 in place of the stud 4 to which it was originally coupled. It will be understood that the adjusting rod 5 extends to the timer of the automobile, which it adjusts by means of a short lever 29 to which said rod 5 is attached.

15 The end of the arm 7 opposite the socket 6 carries another socket 14 within which is adapted to be snapped a ball stud 15 carried by a lever 16, this lever being a part of a 20 collar 17 surrounding and clamped to a sleeve 18 having cam followers 19 thereon. This sleeve 18 in turn surrounds the starter rod 20 on which is a fixed nut 21 against which the lower end of the sleeve 18 rests. Above the 25 sleeve 18 a second sleeve 22 surrounds the starter rod 20, this sleeve 22 having a flange or plate 23 through which screws 24 are threaded, these screws 24 having reduced ends fitting in the threaded bushings 26 which are 30 fixed in the dash 27. Thus the sleeve 22 is restrained from rotative movement. The cam followers 19 cooperate with the cams 28 on the sleeve 22 when the sleeve 18 is rotated, as will be hereinafter more fully described, 35 the followers 19 having a predetermined limit or amount of free travel.

40 The interior of the collar 17 is serrated, to cooperate with serrations on the sleeve 18, as illustrated. Thus the collar 17 and lever 16 may be adjusted to predetermined position on the circumference of the sleeve 18 and then clamped in adjusted position by means of the clamping screw 29.

Below the steering wheel 2 is fixed the spark 45 control rod quadrant 30, normally having an upstanding lug 31 at each end thereof. I break off the lug at the retard end of the quadrant, however, and apply an arcuate plate 32 beneath the said quadrant. This 50 plate is of greater length than the quadrant 30, and has upstanding lugs 33 and 34 at the advance and retard ends thereof respectively. I then position a short arcuate plate 35 on the plate 32, having an end 36 adapted to project 55 slightly over the quadrant 30, the plate 35 and plate 32 being united by means of a screw 37.

60 Thus it is now possible to move the spark control rod to fully retarded position and beyond. After said rod 38 has reached the fully retarded position, it will ride over the plate 35 and will rotate the lever 3 carrying the ball stud 4. This will move the arm 7 to the left, as viewed in Fig. 4, operating the lever 16 to rotate the sleeve 18. After the 65 cam followers 19 have traveled the predeter-

mined distance, they will engage and ride up on the cams 28 forcing the sleeve 18 downwardly. Since the sleeve 18 bears against the nut 21 which is fixed to the starter rod 20, said starter rod 20 will also be depressed to 70 make the desired contact in the starter switch. This depression of the starter rod 20 will, of course, be against the tension of the usual 75 starter rod spring. On returning the spark control rod 38 to normal position, the sleeve 18 will of course be rotated in the opposite direction, and the starter rod spring will raise the starter rod to normal position.

80 When the spark control rod 38 again contacts with the notched portion of the quadrant 30, the starter rod will have been returned to normal position, and the spark will be in retarded position.

85 In moving the arm 7 to the left, as viewed in Fig. 4, when the spark adjusting rod 5 has reached fully retarded position, it becomes desirable to prevent further movement of said rod in that direction. When fully retarded position of the spark adjusting rod has been reached, the yoke 12 will slide 90 along the arm 7 against the tension of the spring 39, this spring 39 being mounted in a recess 40 in the outer end of the arm 7, and being held in place by the projecting arms 13 at one end, and by the lug 41 at the outer 95 end of the recess 40. When the arm 7 is being returned to normal position, however, the yoke 12 will strike against the upturned end of the plate 9 and the spark adjusting rod 5 will again be operated.

100 In many instances operators neglect to open the throttle of an automobile when operating the self-starter. This is particularly true when the engine stalls in traffic. The result is that the engine either will not start, or requires a much longer operation of the self-starter before it starts. In order to overcome this difficulty, I provide novel means to automatically open the throttle before operation of the self-starter. I accomplish this 110 desirable result by providing an arcuate arm 42 having a grooved end 43 and a shorter arcuate arm 44 having a grooved end 45. These grooved ends are adapted to fit over the spark control rod 38 and be clamped in 115 position by a screw 46. This arm 42 is of such a length that when the spark control rod 38 is moved toward starter operating position, as illustrated in dotted lines in Fig. 2, said arm 42 will engage the throttle control rod 47, operating on the quadrant 48 and will move said throttle control rod a few notches toward open position, thus rotating the throttle lever 49 and operating the throttle adjusting rod 50. Thus an increased flow 120 of gasoline to the intake manifold of the engine is automatically provided before contact is made in the starter switch. When the spark control rod is then moved toward advanced position, the throttle rod 47 will re- 125 130

main in the position to which it has been moved, insuring against stalling of the engine. The advantages of this feature will be instantly apparent. Thus my novel de-

5 vice reduces the operations heretofore required to start an automobile engine, to a single operation, viz., manipulation of the spark control rod. This manipulation of said rod retards the spark, opens the throttle
10 and operates the starter switch, a feature which will be greatly appreciated, particularly by owners of Ford automobiles.

The operation of my novel device is simple and will be readily understood, being 15 briefly described as follows: It being desired to start the automobile engine, the ignition switch is turned on, the spark control rod 38 moved to retarded position and then beyond said position, whereupon the sleeve 18 will 20 be rotated and the cam followers 19 will ride on the cams 28, sliding the sleeve downwardly and depressing the starter rod. Simultaneously with the retarding of the spark control rod 38, the throttle control rod 25 47 will be opened slightly. When the spark control rod has reached fully retarded position, movement of the spark adjusting rod 5 beyond that point will be prevented by the yoke 12 sliding on the arm 7, thus preventing 30 injury to the timer. When the engine has started, the spark control rod 38 is moved toward advanced position, leaving the throttle control rod 47 slightly open to provide sufficient gasoline to insure against stalling 35 of the engine.

It will be appreciated and understood that I have devised an efficient and simple apparatus of this nature, one which is economical and simple to install and since I believe 40 this device to be entirely novel, I have therefore claimed the same broadly in the present application.

While I have necessarily described my present invention somewhat in detail, it will 45 be appreciated that I may vary the size, shape and arrangement of parts within reasonably wide limits without departing from the spirit of the invention.

My invention is further described and de- 50 fined in the form of claims as follows:

1. Starter control mechanism of the kind described, comprising a fixed sleeve, cams on said sleeve, a slidable sleeve, cam followers on said second sleeve, each of said sleeves 55 surrounding the starter rod, and means to rotate said slidable sleeve whereby the cam followers thereon will engage the cams on the fixed sleeve and effect a depression of said slidable sleeve.

60 2. Starter control mechanism of the kind described, comprising a fixed sleeve, cams on said sleeve, a slidable sleeve, cam followers on said second sleeve, each of said sleeves surrounding the starter rod, and means oper- 65 able by the spark control rod to rotate said

slidable sleeve whereby the cam followers thereon will engage the cams on the fixed sleeve and effect a depression of said slidable sleeve.

3. Starter control mechanism of the kind 70 described, comprising a fixed sleeve, cams on said sleeve, a slidable sleeve, cam followers on said second sleeve, each of said sleeves surrounding the starter rod, means operable by the spark control rod to rotate said slidable 75 sleeve whereby the cam followers thereon will engage the cams on the fixed sleeve and effect a depression of said slidable sleeve, and means operable by said spark control rod to advance the throttle control rod simultaneously with 80 the depression of said slidable sleeve.

4. Starter control mechanism of the kind described, comprising a fixed sleeve surrounding the starter rod, cams on said sleeve, a 85 slidable sleeve below said fixed sleeve and surrounding the starter rod, cam followers on said lower sleeve, a member fixed to said starter rod and engaged by said lower sleeve, and an arm connected at one end to said lower sleeve and at its other end to the spark control lever.

5. Starter control mechanism of the kind described, comprising a fixed sleeve surrounding the starter rod, cams on said sleeve, a 95 slidable sleeve below said fixed sleeve and surrounding the starter rod, cam followers on said lower sleeve, a member fixed to said starter rod and engaged by said lower sleeve, and an arm pivotally connected at one end to said lower sleeve and pivotally connected at 100 its other end to the spark control lever.

6. Starter control mechanism of the kind described, comprising a fixed sleeve surrounding the starter rod, cams on said sleeve, a 105 slidable sleeve below said fixed sleeve and surrounding the starter rod, cam followers on said lower sleeve, a member fixed to said starter rod and engaged by said lower sleeve, and an arm pivotally connected at one end to said lower sleeve and pivotally connected at 110 its other end to the spark control lever, the normal spark adjusting rod being pivotally connected to said arm.

7. Starter control mechanism of the kind described, comprising a fixed sleeve surrounding the starter rod, cams on said sleeve, a 115 slidable sleeve below said fixed sleeve and surrounding the starter rod, cam followers on said lower sleeve, a member fixed to said starter rod and engaged by said lower sleeve, 120 and an arm pivotally connected at one end to said lower sleeve and pivotally connected at its other end to the spark control lever, the normal spark adjusting rod being pivotally connected to said arm, said spark adjusting 125 rod being movable through a portion only of the movement of said arm.

8. Starter control mechanism of the kind described, comprising a fixed sleeve surrounding the starter rod, cams on said sleeve, a 130

- slidable sleeve below said fixed sleeve and surrounding the starter rod, cam followers on said lower sleeve, a member fixed to said starter rod and engaged by said lower sleeve, an arm connected at one end to said lower sleeve and at its other end to the spark control lever, and means associated with the spark control rod quadrant whereby said spark control rod may be moved beyond normal retarding position. 10. Starter control mechanism of the kind described, comprising a fixed sleeve surrounding the starter rod, cams on said sleeve, a slidable sleeve below said fixed sleeve and surrounding the starter rod, cam followers on said lower sleeve, a member fixed to said starter rod and engaged by said lower sleeve, an arm connected at one end to said lower sleeve and at its other end to the spark control lever, means associated with the spark control rod quadrant whereby said spark control rod may be moved beyond normal retarding position, and means associated with said spark control rod adapted to engage the throttle control rod after the spark control rod has passed its normal retarded position. 11. Starter control mechanism of the kind described, comprising a fixed sleeve surrounding the starter rod, cams on said sleeve, a slidable sleeve below said fixed sleeve and surrounding the starter rod, cam followers on said lower sleeve, a member fixed to said starter rod and engaged by said lower sleeve, an arm connected at one end to said lower sleeve and at its other end to the spark control lever, means associated with the spark control rod quadrant whereby said spark control rod may be moved beyond normal retarding position, and an arcuate arm affixed to said spark control rod adapted to engage the throttle control rod after the spark control rod has passed its normal retarded position. 12. Starter control mechanism of the kind described, comprising a fixed sleeve surrounding the starter rod, cams on said sleeve, a slidable sleeve below said fixed sleeve and surrounding the starter rod, cam followers on said lower sleeve, a member fixed to said starter rod and engaged by said lower sleeve, an arm pivotally connected at one end to said lower sleeve and pivotally connected at its other end to the spark control lever, and a yoke slidably mounted on said arm, the spark adjusting rod being pivotally connected to said yoke. 13. Starter control mechanism of the kind described, comprising a fixed sleeve surrounding the starter rod, cams on said sleeve, a slidable sleeve below said fixed sleeve and surrounding the starter rod, cam followers on said lower sleeve, a member fixed to said starter rod and engaged by said lower sleeve, a lever on said lower sleeve, and an arm pivotally connected at one end to said lever and pivotally connected at its other end to the spark control lever. 14. Starter control mechanism of the kind described, comprising a fixed sleeve surrounding the starter rod, cams on said sleeve, a slidable sleeve below said fixed sleeve and surrounding the starter rod, cam followers on said lower sleeve, a member fixed to said starter rod and engaged by said lower sleeve, an adjustable collar on said lower sleeve, a lever on said collar, and an arm pivotally connected at one end to said lever and pivotally connected at its other end to the spark control lever. 15. Starter control mechanism of the kind described, comprising a fixed sleeve surrounding the starter rod, cams on said sleeve, a slidable sleeve below said fixed sleeve and surrounding the starter rod, cam followers on said lower sleeve, a member fixed to said starter rod and engaged by said lower sleeve, an adjustable collar on said lower sleeve, a lever on said collar, and an arm pivotally connected at one end to said lever and pivotally connected at its other end to the spark control lever, the normal spark adjusting rod being pivotally connected to said arm and being movable throughout a portion only of the movement of said arm. In testimony whereof, I have signed my name to this specification. ALFRED F. JACKSON.
